[57] CLAIM

The ornamental design for a combined control handle and viewing screen for an endoscope, as shown and described.

DESCRIPTION

FIG. 1 is a perspective view of a combined control handle and viewing screen for an endoscope showing our new design;

FIG. 2 is a top plan view;

FIG. 3 is a left side elevation thereof, the right side being a mirror image;

FIG. 4 is a bottom plan view;

FIG. 5 is a rear elevation view thereof; and,

FIG. is a front elevational view thereof.

The broken line showing of the service cord and insert tube in FIG. 1 is for illustrative purposes only and forms no part of the claimed invention.

FIG. 1

FIG. 2

FIG. 3
